UNITED STATES PATENT OFFICE.

JOHN A. LAMONT, OF CHICAGO, ILLINOIS, ASSIGNOR TO AMERICAN STEEL FOUNDRIES, OF CHICAGO, ILLINOIS, A CORPORATION OF NEW JERSEY.

ARTICULATED CAR CONSTRUCTION.

Application filed September 10, 1925. Serial No. 55,419.

This invention relates to an articulated car construction.

One object of the invention is to provide a simple, reliable, durable and efficient articulated car construction whereby car units may be easily connected, whereby said units may have relatively vertical angling movements, whereby said car units may be properly held spaced with respect to each other and prevented from having relative transverse movements, and whereby each car unit may have free pivotal movement upon a center plate under which the truck bolster may pivot.

Another object is to provide a side bearing arrangement for articulated car units adapted to permit relative vertical angling movements between said car units and to resist relative transverse movements between said car units.

Another object is to provide an articulated car construction adapted to meet the various requirements under actual operating conditions.

These and other objects are accomplished by means of the arrangement shown on the accompanying sheets of drawings, in which—

Figure 1 is a fragmentary top plan view of two car units connected in accordance with my invention;

Figure 2 is a fragmentary vertical sectional view taken in the plane of line 2—2 of Figure 1;

Figure 3 is a fragmentary horizontal sectional view taken in the plane of line 3—3 of Figure 2;

Figure 4 is a detail sectional view taken in the plane of line 4—4 of Figure 2;

Figure 5 is a detail vertical sectional view taken in the plane of line 5—5 of Figure 3;

Figure 6 is a top plan view of the interconnected car body units on a smaller scale and showing more detail than shown in Figure 1;

Figure 7 is a partial transverse sectional view taken in the plane of line 7—7 of Figure 6; and

Figure 8 is a detail view taken in the plane of line 8—8 of Figure 6.

The various novel features of the invention will be apparent from the following description and drawings, and will be particularly pointed out in the appended claims.

Referring to the figures of the drawings, it will be noted that my invention is illustrated in connection with an articulated car construction in which there are two car body units which may be represented by the body bolsters 10 and 11. Formed integrally with each of said body bolsters is a center bearing member 12, which center bearing members are centrally longitudinally aligned with respect to the car body units and have their circular bottom portions pivotally arranged with respect to a center plate 13, in turn pivotally mounted upon a central portion of a truck equalizing bolster 14. Each of the center bearing members 12 is pivotally mounted in its own circular bearing pocket 15 in the center bearing plate 13 and said bearing pockets 15 are centrally aligned longitudinal of the car body units. Generally speaking, the lower portions of the center bearing members 12 are cylindrical in shape. The upper portion of each is hollow or recessed as shown at 16 for the reception of an associated member 17, the latter of which is pivotally connected with its center bearing member by a pivot pin 18. Each of said pivot pins 18 is supported within bearing portions 19 and 20 of said center bearing members. One of the members 17 has laterally extending wings 21 terminating in projections 22 which are received within corresponding pockets 23 of the other member 17. These members 17 are interconnected at their winged ends by bolts 24 around which springs 25 are mounted. The tension of the springs is controlled by nuts 26. Accordingly, it will be seen that the members 17 which are pivotally connected to the center bearing members 12 are yieldably interconnected. The inner faces of the projections 22 and the cooperating inner wall of the pocket 23 are curved vertically as shown at 27 so that the members 17 may have relative vertical angling movements. Also in this same connection, the central engaging portions of said members are provided with convex curved surfaces 28 for permitting such relative vertical angling movements. It will be noted that the bolts 24 pass through enlarged openings 29 in one of said members 17 to permit freedom of movement. The members 17 when taken together act as a separator or means for holding the car body units separated from each other as best shown in Figures 105 110

1 and 2. These members 17 which connect the car units not only separate the same but prevent relative transverse movements therebetween. In this connection, it will be noted that the vertical side walls of the projections 22 engage the vertical side walls of the pockets 23 so that relative lateral movement between the members 17 is prevented. As a result of the separator members 17 being interconnected in the manner in which they are, the center plate 13 is held against rotation, but the center bearing members 12 may pivot on said center bearing plate, and the truck bolster 14 may pivot under said center bearing plate 13.

The truck bolster may be a three-piece bolster similar to that shown in my Patent No. 1,377,706, granted on May 10, 1921, in which it will be noted that there are two transverse saddle members 30 formed integrally with the central cross-truck bolster member 14, the saddle members 30 being rockably mounted upon two supported associated transverse bolster members 31. While this truck bolster is for a six-wheel truck, it will be understood that my invention is not limited to a six-wheel truck.

Referring particularly to Figures 6, 7 and 8, it will be noted that the body bolster member 10 is provided with two side bearings 32 which rest upon side bearing members 33 formed on the other body bolster 11. The side bearing members 32 are housed within pocket portions 34 of the side bearing members 33 of body bolster 11. The body bolster 11 is provided with additional side bearings 35 located just inwardly from the side bearings 33 and therebelow, which rest upon rocker blocks 36 formed in a side bearing housing 37 on the truck bolster 14. In this way not only is the side bearing load finally transmitted to the truck bolster but also the car body units are permitted to angle vertically with respect to each other because of the rocker block arrangement 36. These rocker blocks 36 are retained against displacement within the said bearing members 37. The side bearing surface of bearing 32 may be slightly curved 50 also for permitting vertical angling movements.

By means of this simple construction, the car body units are held spaced apart, are permitted to have relative vertical angling movements but are prevented from having relative transverse movements; said car body units may pivot upon the center plate which they have in common and the truck may pivot at the said center plate, all of the parts cooperating in a manner to meet the various requirements under actual service conditions.

It is my intention to cover all modifications of the invention falling within the spirit and scope of the following claims.

I claim:

1. In an articulated car construction, the combination of two car body units, a center bearing member on each unit, a truck bolster, and a center plate pivotally mounted on said bolster and pivotally arranged with respect to each of said center bearing members to form a flexible operating arrangement.

2. In an articulated car construction, the combination of two car body units, a center bearing member on each unit in longitudinal alignment, a truck bolster, and a center plate pivotally mounted on said bolster and having oppositely arranged bearing portions pivotally associated with respect to each of said center bearing members to form a flexible operating arrangement.

3. In an articulated car construction, the combination of two car body units, a center bearing member on each unit, a truck bolster, a center plate pivotally mounted on said bolster and pivotally arranged with respect to each of said center bearing members to form a flexible operating arrangement, and means connecting said center bearing members, acting as a separator between said car body units to resist relative transverse movements between said units and to cause pivotal action between said center plate and bolster in taking curves during car operation.

4. In an articulated car construction, the combination of two car body units, a center bearing member on each unit, a truck bolster, a center plate pivotally mounted on said bolster and pivotally arranged with respect to each of said center bearing members to form a flexible operating arrangement, and means interposed between said car body units to resist relative transverse movements between said units and to cause pivotal action between said center plate and bolster in taking curves during car operation.

5. In an articulated car construction, the combination of two car body units, a center bearing member on each unit, a truck bolster, a center plate pivotally mounted on said bolster and pivotally arranged with respect to each of said center bearing members to form a flexible operating arrangement, and means for resisting relative transverse movements between said car body units during car operation.

6. In an articulated car construction, the combination of two car body units, a center bearing member on each unit, a truck bolster, a center plate pivotally mounted on said bolster and pivotally arranged with respect to each of said center bearing members to form a flexible operating arrangement, and side bearing means for said car body.

7. In an articulated car construction, the combination of two car body units, a center

- bearing member on each unit, a truck bolster, a center plate pivotally mounted on said bolster and pivotally arranged with respect to each of said center bearing members 5 to form a flexible operating arrangement, means interposed between said car body units for resisting relative transverse movement between said car body units, and side bearing members for said car body units.
- 10 8. In an articulated car construction, the combination of two car body units, a center bearing member on each unit, a truck bolster, a center plate pivotally associated with said bolster and pivotally arranged with respect 15 to each of said center bearing members, and cooperating members pivotally connected to said car body units acting as a separator between said units and resisting relative transverse movements between said units.
- 20 9. In an articulated car construction, the combination of two car body units, a center bearing member on each unit, a truck bolster, a center plate pivotally mounted on said bolster and pivotally arranged with respect 25 to each of said center bearing members to form a flexible operating arrangement, and interconnected members pivotally connected respectively to said center bearing members acting as a separator between said car body 30 units and arranged to resist relative transverse movements therebetween.
10. In an articulated car construction, the combination of two car body units, a center bearing member on each unit, a center plate pivotally arranged with respect to each of 35 said center bearing members, and interconnected members respectively connected to said center bearing members and acting as a separator between said car body units to 40 resist relative transverse movement between said units.
11. In an articulated car construction, the combination of two car body units, a center bearing member on each unit, a center plate pivotally associated with each of said center bearing members, and members pivotally connected to said center bearing members to act as a separator between the car body units and having interengaging curved surfaces 45 for permitting relative vertical angling movement between said car body units.
12. In an articulated car construction, the combination of two car body units, a center bearing member on each unit, a center plate pivotally associated with respect to each of 50 said center bearing members, and members respectively connected to said center bearing members and having interfitting portions for preventing relative lateral movement be- 55
- tween said car body units, said members having interengaging curved surfaces for permitting relative vertical angling between said car body units. 60
13. In an articulated car construction, the combination of two car body units, a center bearing member on each unit, a center plate plate pivotally associated with respect to each of said center bearing members, and interassociated members respectively pivotally connected to said center bearing members yieldably connected to each other to permit relative vertical angling movements between said car units. 65
14. In an articulated car construction, the combination of two car body units, a center bearing member on each unit, a truck bolster, a center plate pivotally mounted on said bolster and pivotally arranged with respect to each of said center bearing members, interengaging members respectively connected to said center bearing members arranged to permit relative vertical angling movements between said car body units and to prevent relative transverse movements between said car body units, and side bearing means for 80 said car body units. 85
15. In an articulated car construction, the combination of two car body units, a center bearing member on each unit, a truck bolster, a center plate pivotally associated with said bolster and pivotally arranged with respect to each of said center bearing members, and interengaging side bearing members on said car units. 90
16. In an articulated car construction, the combination of two car body units, a center bearing member on each unit, a truck bolster, a center plate pivotally associated with said bolster and pivotally arranged with respect to each of said center bearing members, interengaging side bearing members on said car units, and a side bearing engagement between one of said car body units and said truck bolster. 95
17. In an articulated car construction, the combination of two car body units, a center bearing member on each unit, a truck bolster, a center plate pivotally associated with said bolster and pivotally arranged with respect to each of said center bearing members, interassociated side bearing members on said car units, and another side bearing member associated with said other under side bearing member and adapted to cooperate with said truck bolster. 100
